UNITED STATES PATENT OFFICE.

WILLIAM W. HARRIS, OF NEW YORK, N. Y., ASSIGNOR TO MAWHINNEY LAST CO., OF BROCKTON, MASSACHUSETTS, A CORPORATION OF MASSACHUSETTS.

ANIMATED TOY.

Application filed March 12, 1925. Serial No. 15,012.

To all whom it may concern:

Be it known that I, WILLIAM W. HARRIS, a citizen of the United States of America, residing at the city, county, and State of 5 New York, have invented certain new and useful Improvements in Animated Toys, of which the following is a specification.

This invention relates to animated toys.

An object of this invention is to devise 10 an animated toy having one or more articulated parts with provision of means for moving such articulated parts by comminuted, weighted material enclosed within the body of the toy.

15 Pursuant to a preferred form of my invention applicable for example to a dog toy the body of the toy is made hollow for receiving a compartment or equivalent for enclosing lead shot or other comminuted weighted material, said compartment being 20 provided with partitions, baffles, shelves or the like forming pockets controlling the flow of the lead shot at predetermined time intervals in one of such pockets the lead 25 shot is initially disposed by suitable manipulation of the body of the toy, and from which one pocket the lead shot slowly flows into another pocket and thus for the remaining one or more pockets. The dog toy 30 may be provided with member representing a tail which may be actuated by the gravitating lead shot for a period and then brought to quiescence.

35 Preferably, the compartment is pivotally mounted within the body of the toy and partition means arranged whereby upon flow of the lead shot to a certain stage, the equilibrium of the pivoted compartment is altered, thus permitting the compartment 40 to move jointly with the enclosed lead shot and thereby actuate a member representing other members of the toy, such as parts representing mechanically the tongue and the eyes, which may be combined as a single 45 member. The pivot of the compartment may also be located to change the equilibrium of the combined body of the toy and of the compartment and enclosed lead shot whereby upon the lead shot attaining a pre- 50 determined height within the compartment the body of the toy as a whole is actuated to a changed position.

55 It will be understood that my invention is applicable to toys representing various animals, human beings or other types in

representation of animate and inanimate objects.

Further features and objects will be more fully understood from the following detail description and the accompanying drawings, 60 in which

Fig. 1 is a perspective view of a toy representing a dog and embodying my invention. The position of the toy shown in this figure is termed hereinafter "the final setting up" position, which in the particular form of my invention as illustrated is attained at the termination of the actuation of the toy;

Fig. 2 is a vertical sectional elevation of 70 Fig. 1;

Fig. 3 is a vertical sectional elevation of the toy dog illustrated in Figs. 1 and 2, but shown in an inverted position;

Fig. 4 is a vertical central section of the 75 aforesaid toy dog, showing the same in a partial or intermediate setting-up position, in which position its mouth is in closed position and its eyes are in visible position. This view indicates an initial stage of the 80 flow of the lead shot from the uppermost pocket of the compartment;

Fig. 5 is a vertical section similar to Fig. 4, but showing the shot at a later stage of its flow from the upper compartment; the 85 mouth having been moved to its open position and its eyes to "closed" position.

Fig. 6 is a sectional elevation on line 6—6 of Fig. 4; and

Fig. 7 is a sectional elevation on line 7—7 90 of Fig. 5.

Referring to Fig. 1, representing a toy dog 10, the rigid body portion may include the trunk portion 11, the haunches 12, the neck and head 13 and the upper fore-legs 14. In the particular embodiment illustrated, the member 15 representing the tail is shown of an articulated form, as by securing the member 15 to one end of the shaft 16 pivotally mounted in suitable openings 17, 18 within the compartment 19. The shaft 16 is provided with a detent 20 which may comprise dual impact members 21, 22, whereby as described more particularly hereinafter the lead shot 23 upon encountering the oppositely disposed impact members 21, 22 cause the shaft to oscillate to and fro. Another articulated member 24 represents the lower hind-legs which may be combined as a unitary member. I have also 100 105 110

illustrated the lower fore-legs 25 as articulated and as combined unitarily.

The aforesaid parts may be formed of tinned iron or other metallic or non-metallic material of suitable characteristics and preferably shaped by punch and die operations. The outer faces of the material are suitably painted, lithographed or the like to represent the hair, the coloring and indications of relief and intaglio effects.

As one form of affording actuation of the articulated members of the toy dog, I provide the compartment 19, pivoted on the pin 26 extending from the opposite faces 15 of the body portion 11. The ends of the pin 26 are swaged or equivalent for holding the pin in position. In the form of the compartment 19 as embodied in the illustrated toy, I form an upper portion 27 of 20 general trapezoidal cross-section as viewed in Fig. 4 and a lower portion 28 of irregular quadrilateral cross-section which may terminate in a lowermost portion 29 of a general triangular cross-section. The lower portion 28 of the compartment 19 may be disposed in off-set relation to the upper portion 27. However, it will be understood that the number of portions of the compartment and the general contour and cross-section 25 may be modified for conforming to the outline of the body of any particular animal or other figure, and for attaining the desired stage or stages of unstable equilibrium or like effects.

30 In the particular form of the toy illustrated in the drawings, the compartment 19 is provided with the partition 30 serving as a sloping shelf or bottom forming a pocket with the baffle 31. The baffle 31 is provided 35 having an opening 32, see Figs. 3 and 7, for restricting by its extent of opening the rate of flow of the lead shot 23 from the pocket through the opening 32. The chute 33 serves to direct the path of flow of the lead shot into the lower portion 28 of the compartment 19.

To dispose the lead shot 23 within the pocket formed by the shelf 30, it is necessary 40 to invert the figure of the dog to the position indicated in Fig. 3, which inverted position is attained from the position of the figure and the disposition of the shot 23 as indicated in Fig. 2 by anti-clockwise rotation of the toy from its position shown in Fig. 2 to its position shown in Fig. 3.

Assuming that the lead shot 23 has been 45 brought into the pocket formed by the shelf 30 and partition 31, the figure of the dog is then moved to its position as shown in Fig. 4 by further anti-clockwise rotation of the body 10 from its position shown in Fig. 3 to its position shown in Fig. 4. The downward inclination of the shelf 30 and the opening 32 of the partition 31 permits the 50 lead shot 23 to gravitate slowly there-

through, as indicated at 23^a, and by the provision of the chute 33, the lead shot as indicated at 23^b are directed to fall alternately upon the impact members 21, 22 of the detent 20, causing the tail 15 to oscillate first 70 in one direction and then in the opposite direction, the movement of which is indicated in Fig. 6, by full outline and dash outline, which oscillation movement is afforded by the pivotal mounting of the shaft 16 of the 75 tail 15.

Upon accumulation of the lead shot as indicated at 23^c, see Fig. 5, within the lower portion 28 of the compartment 19 to a height sufficient to cause an obstruction to the impact members 21, 22 of the detent member 20, the detent member 20 is brought to quiescence, and the tail 15 stops moving.

The formation of the compartment 19 and the location of its pivot 26, in the embodiment illustrated, is such that when but a portion of the lead shot 23 is still remaining within the compartment of the shelf 23, the center of gravity of the combined compartment 19 and of the lead shot 23^c is shifted 80 from the right vertically through the pivot pin 26 to the left-hand side of the plane passing vertically through the pivot pin 26, thereby actuating in counter-clockwise direction the compartment 19 from its position shown in Fig. 4 to its position shown in Fig. 5. To attain actuation of an articulated part upon such movement of the compartment 19, I arrange a member of the toy, such as the member 34 representing the 85 lower jaw and the eyes 35 and pivotally connected therewith the tongue 36, in co-action with the compartment 19 as by the provision of the angle portion 37 of the compartment 19 and the concavely turned 90 end 38 of the jaw and eye member 34, 35. The tongue 36 may similarly be formed of a stamped material, suitably shaped and secured to the stamped metal portion 34 by 95 means of its retaining pin 39. The pin 39 serves also as a pivotal pin for the jaw portion 34. The head 13 of the body of the toy is provided with oppositely disposed openings 40 corresponding to the normal position 100 of the eyes 35 to show the eyes 35 in "open" appearance when the mouth of the toy is in closed position. The member 34 also carries the representation 35^a of the eyes of the toy animal in "closed" appearance as in Fig. 4, the representations 35^a being located to be visible through the openings 40 respectively when the lower jaw is lowered and the tongue 36 fully visible, as 105 in Fig. 5.

Accordingly, upon the change of equilibrium of the compartment 19, the movement of the compartment 19 actuates the combined jaw 34, the eyes 35 and the tongue 36 to move the eyes of the toy from open 110 position to closed position and the jaw 34 115 to closed position and the jaw 34 120 to open position.

from its closed position to its open position. The extent of movement of the compartment 19 will be perceived by a comparison of the position of the compartment 19 in Fig. 5 relative to its position in Fig. 4.

Upon gravitation of additional lead shot 23 from the pocket of the shelf 30, causing increased accumulation of the lead shot 23^c within the lower compartment 28, the center of gravity of the compartment 19 and the accumulated lead shot 23^c combined with the body 10 of the dog is shifted relative to the pivot 41 between the haunch portion 12 and the lower hind feet member 24, causing the body 10 of the dog to move from its position shown in Fig. 5 to its final setting-up position shown in Figs. 1 and 2, by reason of the mechanical connection between the upper corner portion of the compartment 19 with the tongue and eye member 34 and therewith through the pivot pin 39 with the body 10 of the dog toy.

It is desirable in certain circumstances to interconnect one or more articulated members by the medium of resilient means, as for example the expansive spring 42, having its one end secured within the eye 43, its middle or fulcrum portion 44 encircling the pivot pin 41 and its opposite end portion 45 abutting the inner face of the lower hind feet member 24, whereby upon shifting of the center of gravity, the "setting-up" movement of the figure of the dog is accelerated. The spring 42 or equivalent also affords the use of a less quantity of the comminuted material for attaining the actuated effects.

It will be observed that in the event of moving the toy figure from its position as shown in Fig. 2 in clockwise direction to its inverted position, the lead shot 23 will be brought within the compartment 46, see Fig. 3, in which circumstance the center of gravity of the toy will lie to the left vertically of the area of contact of the head portion with the table or other support, and accordingly the combined body 11, the compartment 19 and the lead shot 23 will be brought into unstable equilibrium, causing the toy to fall in a direction to the left of that shown in Fig. 3.

Supplemental to the use of the articulated figure as a toy, a "rhyme" may be formulated, recounting at proper time intervals the movements of articulation of the toy, and emphasizing the giving of "orders" to the toy for the performance of its trick.

It will be observed that the opening 32 of the partition or baffle 31 is sufficiently large to preclude "bridging" of the lead shot 23 or other comminuted material and the rate of flow of the lead shot through the opening 32 is regulated by the degree of general inclination of the chute 33. The chute 33 may be turned upwardly as may be desired

as is indicated adjacent the free end of the chute to form an upward incline to a regulated extent and thereby retard the flow of lead shot down the chute and therewith retard the rate of flow of the lead shot 70 through the opening 32.

It will be apparent that my invention is applicable to other types of figures representing animate or inanimate objects and one or more movably mounted members provided for attaining actuation of the same in similitude of articulation as desired.

Whereas, I have described my invention by reference to specific form thereof, it will be understood that many changes and modifications may be made without departing from the spirit of the invention.

I claim

1. The combination of a hollow body representing a figure, a closed compartment disposed within said hollow body, comminuted weighted material enclosed within said compartment, means disposed in said compartment for providing a gradual discharge of the comminuted weighted material from an upper location within said compartment to a lower location within said compartment, means for pivotally mounting said compartment within said hollow body for attaining a plurality of positions of equilibrium of said compartment and of the comminuted material for varying positions of accumulation of the comminuted material within said compartment and means for movably connecting a portion of said compartment remote from said pivotal mounting with said hollow body whereby upon the attainment of a change of position of equilibrium of said compartment said hollow body is moved from one position to another position.

2. The combination of a hollow body representing a figure, a closed compartment disposed within said hollow body, baffle means disposed within said compartment disposed in downwardly sloping positions for varying positions of said compartment, comminuted weighted material enclosed within said compartment, means for pivotally mounting said compartment within said hollow body for attaining a plurality of positions of equilibrium of said compartment and of the comminuted material for varying positions of accumulation of the comminuted material within said compartment and means for movably connecting a portion of said compartment remote from said pivotal mounting with said hollow body whereby upon the attainment of a change of position of equilibrium of said compartment said hollow body is moved from one position to another position.

3. The combination of a hollow body representing a figure, a member movably mounted on said hollow body representing an articulated member of the figure, a closed

- compartment disposed within said hollow body, comminuted weighted material enclosed within said compartment, means disposed in said compartment for providing a gradual discharge of the comminuted weighted material from an upper location within said compartment to a lower location within said compartment, means for pivotally mounting said compartment within said hollow body for attaining a plurality of positions of equilibrium of said compartment and of the comminuted material for varying positions of accumulation of the comminuted material within said compartment whereby said articulated member is actuated and means for movably connecting a portion of said compartment remote from said pivotal mounting with said hollow body whereby upon the attainment of a change of position of equilibrium of said compartment said hollow body is moved from one position to another position.
4. The combination of a hollow body representing a figure, a member movably carried by said hollow body and representing an articulated member of the figure, gravity material disposed within said hollow body, means for retaining gravity material within said hollow body, means carried by said hollow body for providing a gradual discharge of the gravity material from an upper location to a lower location, means actuated by said gravity material upon falling for actuating said articulated member and means for movably connecting a portion of said compartment remote from said pivotal mounting with said hollow body whereby upon the attainment of a change of position of equilibrium of said compartment said hollow body is moved from one position to another position.
5. The combination of a hollow body representing a figure, a closed compartment disposed within said hollow body, gravity material enclosed within said closed compartment, a member movably carried by said hollow body and representing an articulated member of the figure, means for mounting said member to provide for the actuation of said member upon the movement of said closed compartment, means disposed within said compartment for providing a gradual discharge of the gravity material from an upper location to a lower location, means for pivotally mounting said closed compartment for attaining movement of said closed compartment for varying positions of the gravity material therein whereby upon movement of said closed compartment said articulated member is actuated and means for movably connecting a portion of said compartment remote from said pivotal mounting with said hollow body whereby upon the attainment of a change of position of equilibrium of said compartment

said hollow body is moved from one position to another position.

6. The combination of a hollow body representing a figure, a member movably carried by said hollow body and representing an articulated member of the figure, a closed compartment, means for movably mounting said closed compartment within said hollow body, means for mounting said member to provide for the actuation of said member upon the movement of said closed compartment, gravity material disposed within said closed compartment, means providing for the gradual discharge of said gravity material from an upper location within said closed compartment to a lower location within said closed compartment, means connecting said closed compartment with said articulated member whereby upon movement of said closed compartment said articulated member is actuated and means for movably connecting a portion of said compartment remote from said pivotal mounting with said hollow body whereby upon the attainment of a change of position of equilibrium of said compartment said hollow body is moved from one position to another position.

7. The combination of a hollow body representing a figure, means for movably supporting said hollow body, a member movably carried by said hollow body and representing an articulated member, a closed compartment, gravity material disposed within said closed compartment, means for movably connecting said compartment with said hollow body, means for mounting said member to provide for the actuation of said member upon the movement of said closed compartment, means disposed within said closed compartment for providing for a gradual discharge of said gravity material from an upper location within said closed compartment to a lower location within said closed compartment and means for movably mounting said closed compartment within said hollow body for attaining varying positions for varying portions of the mass of the gravity material at said upper location and said lower location respectively within said closed compartment to thereby effect the movement of said closed compartment to actuate said articulated member and said hollow body from an inclined position to upright position.

8. The combination of a hollow body representing a figure, means for movably supporting said hollow body, a member movably carried on said hollow body and representing an articulated member of the figure, a closed compartment, means for movably connecting said compartment with said hollow body, means for mounting said member to provide for the actuation of said member upon the movement of said closed com-

partment, gravity material disposed within said closed compartment, means disposed within said closed compartment for providing for a gradual discharge of said gravity material from an upper location to a lower location and means for pivotally mounting said closed compartment within said hollow body for attaining a plurality of states of equilibrium and consequent movement of said closed compartment to thereby actuate said articulated member and to move said hollow body from an inclined position to upright position.

9. The combination of a hollow body representing a figure, means for movably supporting said hollow body, a member movably carried on said hollow body and representing an articulated member of the figure, a closed compartment, means for movably connecting said compartment with said hollow body, means for mounting said member to provide for the actuation of said member upon the movement of said closed compartment, gravity material disposed within said closed compartment, means disposed within said closed compartment for providing for a gradual discharge of said gravity material from an upper location to a lower location and means for pivotally mounting said closed compartment within said hollow body for attaining a plurality of states of equilibrium and consequent movement of said closed compartment to thereby actuate said articulated member and to move said hollow body from an inclined position to upright position in sequence.

10. The combination of a hollow body representing a figure, a plurality of members movably carried by said hollow body and representing different articulated members of the figure gravity material, a closed compartment provided with baffle means, means for pivotally mounting said closed compartment within said hollow body for attaining a downward slope of said baffle means for one position of said closed compartment, means for movably connecting said compartment with said hollow body, means engaged by said gravity material upon gravitation from said baffle means for actuating one of said articulated members and means responsive upon the accumulation by gravitation of said gravity material within said closed compartment for moving said hollow body from an inclined position to upright position.

11. The combination of a hollow body representing a figure, a member movably carried by said body and representing an articulated member of the figure, comminuted material enclosed within said hollow body, means providing for restricted gravitation of said comminuted material and means disposed in the path of gravitation of said comminuted material and operated thereby for moving said articulated member.

12. The combination of a hollow body representing a figure, a member movably carried by said body and representing an articulated member of the figure, comminuted material enclosed within said hollow body, means disposed in said hollow body for providing the continuous flow of the comminuted material from an upper location within said hollow body to a lower location within said hollow body, means for regulating the extent of the continuous flow of said comminuted material in said hollow body, and means disposed in the path of flow of said comminuted material and operated thereby for moving said articulated member.

13. The combination of a hollow body representing a figure, a member movably carried by said body and representing an articulated member of the figure, comminuted material enclosed within said hollow body, means disposed in said hollow body for providing the continuous flow of the comminuted material from an upper location within said hollow body to a lower location within said hollow body, means controlling the path of said comminuted material and regulating the extent of the continuous flow of said comminuted material in said hollow body and means disposed in the path of gravitation of said comminuted material and operated thereby for moving said articulated member.

14. The combination of a hollow body representing a figure, a member movably carried by said body and representing an articulated member of the figure, comminuted material enclosed within said hollow body, means disposed in said hollow body for providing the continuous flow of the comminuted material from an upper location within said hollow body to a lower location within said hollow body, regulated means controlling the path of said comminuted material and regulating the extent of the continuous flow of said comminuted material in said hollow body and means disposed in the path of gravitation of said comminuted material and operated thereby for moving said articulated member.

15. The combination of a hollow body representing a figure, a member rotatably supported by said body and representing an articulated member of the figure, comminuted material enclosed within said hollow body, means disposed in said hollow body for providing the continuous flow of the comminuted material from an upper location within said hollow body to a lower location within said hollow body, regulated means having a restricted opening controlling the path of said comminuted material and regulating the extent of the continuous flow of said comminuted material in said hollow body and means disposed in the path

of gravitation of said comminuted material and operated thereby for rotating said articulated member.

16. The combination of a hollow body representing a figure, a member oscillatingly supported by said body and representing an articulated member of the figure, comminuted material enclosed within said hollow body, means disposed in said hollow body for providing the continuous flow of the comminuted material from an upper location within said hollow body to a lower location within said hollow body, means controlling the rate of said comminuted material and regulating the extent of the continuous flow of said comminuted material in said hollow body, said controlling means comprising an inclined member for supporting said comminuted material, baffle means provided with an opening and a regulatable chute, and means disposed in the path of gravitation of said comminuted material and operated thereby for oscillating said articulated member.
17. The combination of a body representing a figure, a closed compartment, gravity material, means disposed within said closed compartment for providing a gradual discharge of said gravity material from an upper location within said compartment to a lower location within said compartment, means for movably connecting said compartment with said body, and means for mounting said closed compartment on said body for effecting a plurality of positions of equilibrium of said closed compartment and the consequent actuation of said movably connecting means and the movement of said closed compartment from one position to another.
18. The combination of a body representing a figure, a closed compartment including an upper compartment portion extending laterally of a lower compartment portion, gravity material, means disposed in said upper compartment portion providing for a gradual discharge of said gravity material from said upper compartment portion into

said lower compartment portion and means for pivotally mounting said compartment on said figure extending intermediate said upper compartment portion and said lower compartment portion.

19. The combination of a hollow body representing a figure, means for movably supporting said hollow body, a compartment disposed within said hollow body, gravity material, means disposed in said compartment for providing a gradual discharge of said gravity material from an upper location to a lower location, means movably connecting said compartment with said hollow body, and means for pivotally mounting said compartment on said hollow body for attaining a plurality of positions of equilibrium of said compartment and of said gravity material for varying positions of said gravity material at said upper location and said lower location and for effecting the actuation of said movably connecting means and thereby the movement of said hollow body.

20. The combination of a hollow body representing a figure, means for movably supporting said hollow body, a compartment disposed within said hollow body, gravity material, means disposed in said compartment for providing a gradual discharge of said gravity material from an upper location to a lower location, means movably connecting said compartment with said hollow body, and means for pivotally mounting said closed compartment on said hollow body for attaining a plurality of positions of equilibrium of said compartment and of said gravity material for varying positions of said gravity material at said upper location and said lower location within said closed compartment and for effecting the actuation of said movably connecting means and thereby the movement of said hollow body from an inclined position to an upright position.

In testimony whereof I have signed this specification this 12th day of March, 1925.

WILLIAM W. HARRIS.
